UNITED STATES PATENT OFFICE.

JOSEPH EASTMAN, OF MANITOWOC, WISCONSIN.

NOZZLE-HOLDER.

1,393,098.

Specification of Letters Patent. Patented Oct. 11, 1921.

Application filed November 8, 1920. Serial No. 422,484.

To all whom it may concern:

Be it known that I, JOSEPH EASTMAN, a citizen of the United States, and resident of Manitowoc, in the county of Manitowoc and 5 State of Wisconsin, have invented certain new and useful Improvements in Nozzle-Holders; and I do hereby declare that the following is a full, clear, and exact description thereof.

10 My invention relates to means for supporting the nozzle of a flexible sprinkling main when sprinkling lawns or gardens.

The object of my invention is to provide a support of the character described, so constructed as to be capable of supporting the nozzle at any desired distance from the ground and at any angle thereto.

15 A further object of my invention is to provide a nozzle supporting element that is capable of receiving nozzles of different sizes.

In the accompanying drawings:

Figure 1 represents a side elevation of a 20 hose support embodying the features of my invention, with parts in section to more clearly show the structural features, there being shown a hose nozzle fitted thereto.

Fig. 2 is a plan view of the same with certain parts in section.

25 Fig. 3 is a detail cross section showing the manner in which the clip portion of the support engages the hose nozzle.

Fig. 4 illustrates a side elevation of another form of my invention, and

30 Fig. 5 is a face view of the same, illustrating a hose nozzle in dotted lines fitted therein.

Referring by characters to the drawings, 35 1 designates a metallic spindle having its lower end sharpened, for the purpose of inserting the same in the ground at any predetermined depth or angle. The upper end 7 of the spindle is threaded for the reception of a shoulder nut 8, and fitted over the

40 threaded end is a spring clip 9 having circular apertures 10—10 therein, for the reception of a knurled collar 11 of a hose nozzle.

45 The lower end of the clip is apertured for engagement with the spindle, and said lower end is flattened to form a foot 12, which is adapted to rest upon the face of the nut 8. The foot 12 terminates with a downward toe 13. The upper foot 14 of the clip is apertured and is arranged to be engaged by a 50 thumb nut 15, which is in threaded union

with the upper end 7 of the spindle, as shown. Obviously, the yieldable spring clip can be adjusted to fit various sized nozzles, and owing to the slot 10 formed in the body of the clip, the nozzle is thereby firmly held 60 so as to prevent wobble or endwise movement.

Figs. 4 and 5 of the drawings illustrate another form of my invention wherein the spindle 1 has a reduced portion upon which 65 is placed a gripping element after which the end of the reduced portion is flattened out, as indicated at 2.

The gripping element is formed of a substantially U-shaped member 3 made of resilient metal and of a width sufficient to hold the nozzle securely.

70 The legs of the member 3 have adjacent their ends, the elongated opening 4, through which passes a bolt 5, the same being held in place by the winged nut 6 whereby the legs of the U-shaped member may be drawn together and grip the nozzle as shown at Fig. 2.

In both forms of my invention, it will be 80 understood that the nozzle may be raised or lowered from the ground by merely withdrawing the spindle 1 therefrom, or forcing it deeper, as the case may be. Furthermore, the nozzle may be turned in any 85 direction or at any desired angle to the ground by the position and angle that the spindle is inserted in the ground.

From the foregoing, it is thought that the 90 construction, operation and many advantages of the herein described invention will be apparent to those skilled in the art, without further description, and it will be understood that various changes in the size, shape, proportion and minor details of construction, 95 may be resorted to without departing from the spirit or sacrificing any of the advantages of the invention.

I claim;

1. An article of the class described comprising a spindle, one end of which is pointed and having its opposite end threaded, a shoulder carried by the threaded end of said spindle, an open clip adapted to encompass a hose nozzle having circular slots 100 therein, an apertured foot extending from the clip and fitting over the spindle in abutting engagement with the shoulder thereof, a toe extending from the foot engageable 105 with the shoulder whereby the clip is held 110

against rotation, a second apertured foot extending from the clip body and engaging the threaded spindle end, and an adjusting nut for compressing the foot whereby the 5 clip is contracted about the hose nozzle.

2. An article of the class described comprising a spindle, having one end pointed and the opposite end threaded, a circular skeleton clip body adapted to surround a 10 nozzle, the clip body having apertured feet extending therefrom through which the

threaded end of the spindle projects, a shoulder carried by the spindle for engagement with one of the feet, and a nut in threaded union with the spindle for engagement with 15 the other foot, whereby the clip may be predeterminedly contracted.

In testimony that I claim the foregoing I have hereunto set my hand at Manitowoc, in the county of Manitowoc and State of 20 Wisconsin.

JOSEPH EASTMAN.
